UNITED STATES PATENT OFFICE

141,128

DESIGN FOR A BASE CABINET

Jacques Stanitz, Warren, Ohio, assignor to Mullins Manufacturing Corporation, Salem, Ohio, a corporation of New York

Application March 2, 1945, Serial No. 118,223

Term of patent 7 years

(CL D33—19)

To all whom it may concern:

Be it known that I, Jacques Stanitz, a citizen of the United States, residing at Warren, in the county of Trumbull and State of Ohio, have invented a new, original, and ornamental Design for Base Cabinet, of which the following is a specification, reference being had to the accompanying drawing forming part thereof.

The single figure in the drawing is a perspective view of a base cabinet showing my new design. The rear of the cabinet, not shown, is plain and the other side thereof is the same as illustrated. The characteristic features of my design are shown by means of full lines in the drawing.

I claim:

The ornamental design for a base cabinet, substantially as shown and described.

JACQUES STANITZ.
